DESIGN FOR A COMBINATION COAT AND VEST

Louis C. Solo, Philadelphia, Pa.

Application November 16, 1937, Serial No. 72,931

Term of patent 14 years

To all whom it may concern:

Be it known that I, Louis C. Solo, a citizen of the United States, residing at Philadelphia, in the county of Philadelphia and State of Pennsylvania, have invented a new, original, and ornamental Design for a Combination Coat and Vest, of which the following is a specification, reference being had to the accompanying drawing, forming part thereof.

The vest is an integral part of the coat.

I claim:

The ornamental design for a combination coat and vest substantially as shown and described.

LOUIS C. SOLO.
